CLAIM

The ornamental design for the lighting fixture, as shown and described.

DESCRIPTION

FIG. 1 is a perspective view taken from the front, bottom, and right side of the lighting fixture;

FIG. 2 is a perspective view taken from the front, bottom, and right side of a second embodiment of the lighting fixture, which is essentially twice the length of the first embodiment; and,

FIG. 3 is a bottom plan view of the second embodiment of the lighting fixture.

The broken lines are shown for illustrative purposes only and form no part of the claimed design.
